APPARATUS FOR CRACKING PETROLEUM OIL

Original Filed July 31, 1922

UNITED STATES PATENT OFFICE

2,112,360

APPARATUS FOR CRACKING PETROLEUM
OIL

Carbon P. Dubbs, Newstead, Paget, Bermuda, assignor to Universal Oil Products Company, Chicago, Ill., a corporation of Delaware

Original application July 31, 1922, Serial No. 578,705. Divided and this application May 21, 1936, Serial No. 81,085

3 Claims. (Cl. 196—107)

This application is a division of my co-pending application Serial No. 578,705, filed July 31, 1922.

This invention relates more particularly to apparatus for the conversion of higher boiling petroleum oil into lower boiling point products.

Among the salient objects of the invention are to provide apparatus in which the oil vapors generated in an expansion or vaporizing chamber are relieved of their higher boiling point fractions in a dephlegmating zone so constructed to reduce the superheat of the vapors and separate out the higher boiling point products, and further controlling the temperatures of dephlegmation so that a more uniform and better quality distillate passes over to the final condensing stage.

In the drawing, the single figure is a diagrammatic side elevational view of the apparatus.

Referring in detail to the drawing, the oil to be treated is introduced through the line 1 which has separate connections 2, 3 and 4, controlled by valves 5, 6 and 7, respectively, to manifolds 8, 9 and 10. The manifolds 9 and 10 are connected to circular roses or sprays 11 and 12, while the discharge end of the manifold 8 extends through the T connection 13 and into the vapor line 14 in the form of a perforated pipe 15.

In introducing the oil to the system, it may be charged into the manifold 10 near the top of the dephlegmator 16 or into the manifold 9 which is positioned intermediate of the top and bottom of the refluxing column, or it may be charged through the lower manifold and into the vapor line through the perforated pipe 15 where it is charged near the bottom of the dephlegmator directly into the vapor line.

The oil combined with what condensate it may separate from the vapors in the dephlegmating stage, will collect in the dephlegmator leg 17 from which it is drawn off through the line 18, controlled by the valve 19, and directed to the heating coils 20 mounted in the furnace 21. A connecting pipe 22, controlled by valve 23, furnishes a means for supplying additional raw oil 45 to the charging line, if desired. After passing through the continuous coil 20 in the furnace, the temperature of the oil has been raised to a cracking heat, and in this condition it is introduced in a fluid state to the vaporizing chamber 24. In this enlarged chamber the oil is permitted to collect, the vapors evolved passing off through the vapor line 14 and the liquid unvaporized products being drawn off through the line 25 which is regulated by the valve 26. The vapors 55 passing through the dephlegmator 16 are sub-

jected to the refluxing action of the raw oil or returned condensate which is introduced to the dephlegmator through the manifolds 8, 9 and 10 as explained. In the dephlegmating or refluxing zone there is separated from the oil vapors the 5 higher boiling point fractions undesirable to the production of a low boiling point distillate.

At the bottom of the dephlegmator leg in addition to the draw-off line 18 is a second draw-off line 27 which is controlled by valve 28 through 10 which a portion of the condensates separated out in the dephlegmator together with quantities of raw oil which it may contain, may be drawn from the dephlegmator. This oil directed through the line 27 may be passed through a 15 cooler 29, thence through a line 30 regulated by a valve 31 to a charging pump 32 from which it is pumped through the line 33 to any one or all of the manifolds 8, 9 and 10 which are connected to the line 33 by secondary connections 20 34, 35 and 36. The amount of condensate returned in this manner to the separate manifolds may be regulated by the valves 37, 38 and 39 interposed in the secondary connections. Thus, it is obvious that in addition to the introduction 25 of raw oil to the manifold, the condensate may be also returned and introduced in regulated quantities with the raw oil so that an accurate control may be had over the temperature conditions maintained in the dephlegmating column at 30 all times.

The vapors which remain uncondensed in the dephlegmator pass over through the line 40 in which is interposed a valve 41, to the water condenser coil 42 mounted in the condenser box 43. 35 The discharge end of the condenser coil is connected by a line 44, regulated by a valve 45, to a distillate receiving tank 46. The tank is equipped with pressure relief valve 47, pressure gauge 48, liquid level gauge 49. A liquid draw-off line 50 connected to the bottom of the tank is controlled by a valve 51, and is connected to the suction side of a pump 52 by means of which the distillate may be charged back through the line 53 to any of the manifolds 8, 9 or 10 through 40 the separate connections 54, 55 and 56, which are controlled by suitable valves. A line 57 is connected to the draw-off line 50 and is controlled by the valve 58 whereby the distillate from the receiving tank may be withdrawn from 45 the system instead of recycling it through the dephlegmating stage.

When the vapors from the expansion chamber are discharged into the bottom of the dephlegmator without preliminary cooling, the excess

heat contained therein seriously interferes with the dephlegmating or proper refluxing of the vapors so that the dephlegmator cannot efficiently separate or sift out the higher boiling point fractions. Thus, owing to the superheat or excess heat of the vapors from the reacting or vaporizing chamber, a greater part of the dephlegmator is used for extracting this excess heat before a substantial amount of reflux condensation can take place. For this reason, the superheat of the incoming vapors must be reduced, and this absorption of heat by the refluxing column exhausts to a great extent the cooling capacity of the dephlegmator, thereby reducing to that extent the effectiveness of the apparatus in separating out the higher boiling point vapors. By cooling the vapors sufficiently before or just after they enter the dephlegmator a much more satisfactory separation of the higher boiling point fractions may be obtained.

It has been found that by controlling the capacity of the dephlegmating stage through the introduction of cool oil in different parts of the dephlegmator a more satisfactory separation is obtained than when an apparatus, dependent upon a radiating surface exposed to air, for controlling the capacity of the dephlegmating stage, is used.

It will be noted that by the pipe arrangement shown, it is possible to cool or extract the superheat from the vapors in the vapor line prior to their entering the dephlegmator or into the lower part of the dephlegmator. In doing this the cool oil is introduced through the perforated pipe 15, this oil consisting of the raw oil or combined feed or raw oil, returned condensate, or a combination of the raw oil, reflux condensate and pressure distillate from the receiving tank.

Further dephlegmation is obtained by introducing regulated combinations of the oils mentioned to different heights in the dephlegmator.

It is understood, of course, that oils differ in respect to their treatment, and the control of the dephlegmation will likewise necessarily be altered with the different types of oil treated. By proportioning the amount of cooling in the different parts of the refluxing stage, a more satisfactory and complete control for sifting of the vapors can be obtained, and allows the capacity of a given size dephlegmator to be substantially varied, for example—assume that the vapors in the vapor line have a temperature of from 800° to 820° F.,

these vapors may be cooled by the introduction of a cooling oil near the bottom of the dephlegmator to temperatures ranging from 600° to 700° F., which will condense a large part of the vapors having high boiling point fractions, while the remaining vapors having high boiling point cuts are condensed and thus separated out in the dephlegmator proper by regulated amounts of cool oil supplied through the upper manifold. It will be recognized that the temperatures of the vapors entering the dephlegmator can be maintained at practically any desired degree regardless of how much higher in temperature they may be as they leave the expansion chamber.

The particular design of the apparatus may be varied in numerous ways without departing from the principles involved.

I claim as my invention:

1. An oil cracking apparatus comprising a heating coil and an enlarged chamber communicating therewith, a fractionator and means for passing vapors from the chamber to the fractionator, a condenser and receiver communicating with the fractionator, means for removing reflux condensate from the fractionator, and means for introducing charging oil, condensate from said receiver, and portions of said reflux condensate into contact with said vapors prior to their introduction to the fractionator.

2. An oil cracking apparatus comprising a heating coil and an enlarged chamber communicating therewith, a fractionator and means for passing vapors from the chamber to the fractionator, a condenser communicating with the fractionator, means for contacting condensate formed in said condenser with said vapors prior to their introduction to the fractionator, and means for returning reflux condensate from the fractionator to said coil.

3. An oil cracking apparatus comprising a heating coil and an enlarged chamber communicating therewith, a fractionator and means for passing vapors from the chamber to the fractionator, a condenser communicating with the fractionator, means for contacting condensate formed in said condenser with said vapors prior to their introduction to the fractionator, means for introducing additional condensate formed in said condenser into the fractionator, and means for returning reflux condensate from the fractionator to said coil.
